UNITED STATES PATENT OFFICE.

GEORGE H. CLEMMER, OF ARCANUM, OHIO.

FODDER-PRESS.

SPECIFICATION forming part of Letters Patent No. 371,739, dated October 18, 1887.

Application filed August 3, 1887. Serial No. 246,043. (No model.)

To all whom it may concern:

Be it known that I, GEORGE H. CLEMMER, of Arcanum, in the county of Darke and State of Ohio, have invented a certain new and useful Improvement in Fodder-Presses, of which the following is a specification.

The object of my improvement is to provide a fodder-press whereby greater power, efficiency, and convenience in use are obtainable than usual.

I will first describe in detail a fodder-press embodying my improvement, and then point out the various features of the improvement in the claims.

15 Reference is to be had to the accompanying drawings, forming a part of this specification, in which similar letters of reference designate corresponding parts in both the figures.

Figure 1 is a side view of a fodder-press 20 embodying my improvement when open. Fig. 2 is a partly-sectional side view of the said press when closed.

The base A of the press is formed of two sills, B, supported at the ends, parallel with 25 25 slightly separate from each other, on sleepers C.

The presser-heads D E consist of rigid frames arranged edgewise with the length of the base, having concave jaws F and downward 30 extensions G, received in the longitudinal slot formed between the parallel sills B. The extensions G of the presser-head D are pinned to the sills B to fix said presser-head firmly in place. The extensions G of the presser-head E are fitted to slide lengthwise in said slot, and have laterally-projecting guides H 35 just above and below the sills, so as to hold the presser-head E from any movement in the vertical plane, while allowing it to ride freely lengthwise of the base. A stop, I, passed 40 transversely through the sills, limits the rearward movement of the presser-head E.

A handle-lever, J, is pivoted to a bracket, K, secured to the end of the base opposite the 45 presser-heads, and is connected by a rod, L, with the movable presser-head E.

The pin M, connecting the rod L with the head E, rides in an inclined slot, N, formed in the same, and terminating at its upper end in 50 a forward-extending horizontal shoulder, O. The rod P connects the pin M with the short arm R of an angle-bar, Q, which is pivoted at its vertex to the top of the presser-head E, and has a long arm, S.

55 In opening the press to receive the fodder

the lever J is drawn outward, bringing the pin M to the lower end of the inclined slot N, raising the longer arm of the angle-bar Q to an upright position, and retracting the sliding presser-head, as shown in full lines in 60 Fig. 1. The fodder being then placed in the base between the presser-heads, the lever J is pushed forward, the first result being to push the pin M to the upper end of the slot N and swing the longer arm of the bar Q to a horizontal position, in which it is locked by the pin M engaging the shoulder O. The presser-head E then moves forward to compress the fodder between it and the presser-head D, the arms S of the angle-bar Q serving as a keeper 65 to confine the fodder between the approaching jaws F, as indicated in dotted lines in Fig. 1. When the jaws F meet, the pivot connecting the rod L with the lever J comes in line with the pin M and the main pivot of 70 the lever J, thus automatically locking the movable presser-head against retraction, except by means of the lever J.

Hook-lugs T on the stationary presser-head and on the base A serve to hold the binding-cord beneath the fodder in position to tie up the same when pressed into a bundle, as described.

Having thus described my invention, I claim as new and desire to secure by Letters Patent—

1. In a fodder-press, the combination of a 85 base, two presser-heads, one of which is mounted to slide on the base toward the other, an operating-lever pivoted to the base, and a connecting-rod pivotally connected at one end to the operating-lever and at the 90 other end to the said sliding presser-head, substantially as described.

2. In a fodder-press, the combination of a movable presser-head, E, a hand-lever, J, a swinging keeper on the presser-head E, and operating devices connecting the lever J with the presser-head E and the swinging keeper, substantially as described.

3. In a fodder-press, the combination of a presser-head, E, having an inclined slot, N, 100 terminating in a horizontal shoulder, O, a pivotal angle-bar, Q, a rod, P, a rod, L, connected by the rod P with the angle-bar Q, a pin, M, riding in the slot N and connected to the rod P and rod L, and a lever, J, pivoted to the rod L, substantially as described.

GEORGE H. CLEMMER.
